DESIGN FOR A HEATER

Kenneth H. Brown and Luke L. Harle,
Cleveland, Tenn.

Application August 13, 1945, Serial No. 121,400

Term of patent 7 years

(Cl. D81—19)

To all whom it may concern:

Be it known that we, Kenneth H. Brown and Luke L. Harle, both citizens of the United States and both residents of Cleveland, in the county of Bradley and State of Tennessee, have invented a new, original, and ornamental Design for a Heater, of which the following is a specification, reference being had to the accompanying drawing, forming part thereof.

The figure is a perspective view of a heater showing our new design.

The right side of the article not shown is substantially like the side shown.

We claim:

The ornamental design for a heater, as shown and described.

KENNETH H. BROWN.
LUKE L. HARLE.
